TICKET PUNCH

Alfred R. Jorgenson, Chicago, Ill.

Application May 18, 1933, Serial No. 671,730

13 Claims. (Cl. 164—120)

The invention relates to ticket punches and the primary object of the invention is to provide an improved ticket punch for railroad conductors, etc.

5 A particular object of the invention is to provide an improved ticket punch which is of such construction that it will indicate when it has been actuated improperly to punch a ticket.

One form of the invention is embodied in a 10 ticket punch which comprises a punch member adapted to sever "rides" or similar units from a large ticket which comprises a plurality of such "rides" or small units. The ticket punch is provided with means for indicating each time 15 that it is actuated, properly or improperly, to sever a "ride" or unit from a ticket. Other means on the ticket punch indicates each time the ticket punch is employed properly to punch a "ride" or unit from the ticket. The indicating means 20 preferably comprise counting devices and it will be understood readily that the record of the number of times that the punch has been actuated properly may be subtracted from the total number of times the ticket punch has been operated so that the number of times the ticket punch 25 has been actuated improperly will be known.

Another form of the invention is embodied in a ticket punch which comprises a counting device for indicating the total number of times the 30 ticket punch is employed improperly to punch tickets.

The main advantage of a punch which embodies the invention is that it will indicate each time the punch is employed improperly whether 35 such improper actuation is due to carelessness or to an attempt to defraud the railroad company, etc.

Other objects and advantages will become apparent as the following detailed description progresses, reference being had to the accompanying drawings, wherein—

Fig. 1 is a side elevation of a ticket punch which embodies the invention.

Fig. 2 is a fragmentary side elevation of the 45 punch shown in Fig. 1, a portion of a housing on the punch being broken away to illustrate certain mechanism of the punch.

Fig. 3 is a section taken on line 3—3 of Fig. 2.

Fig. 4 is a fragmentary view illustrating the 50 mechanism in Fig. 2 in changed position.

Fig. 5 is a side view of a punch member which forms part of the improved punch shown in Figs. 1 to 4, inclusive.

Fig. 6 is a section taken on line 6—6 of Fig. 5, 55 portions of the jaws of the punch being shown.

Fig. 7 is a section taken on the same line as Fig. 6, but showing certain parts of the punch in changed positions.

Fig. 8 is a section taken on line 8—8 of Fig. 2.

Fig. 9 is a perspective view of a punch member which forms part of the improved punch shown in Fig. 1.

Fig. 10 is a fragmentary view of a ticket adapted to be employed in connection with the improved punch shown in Figs. 1 to 9, inclusive.

Fig. 11 is a view of a "ride" or a unit severed from the ticket.

Fig. 12 is a fragmentary view of a ticket punch which embodies another form of the invention, a housing on the punch being broken away to illustrate certain mechanism of the punch.

Fig. 13 is a fragmentary view taken on the same line as Fig. 12 illustrating certain parts of the punch in changed positions, and

Fig. 14 is a fragmentary plan view of the punch shown in Figs. 12 and 13, the above mentioned housing being broken away to illustrate the construction of the punch.

Part of the improved mechanism shown in the accompanying drawings is similar to that shown 25 and described in a co-pending application, Serial Number 576,602, filed November 21, 1931 by Alfred R. Jorgenson and Ralph O. Moody.

Referring for the present to Figs. 1 to 9, inclusive, wherein a ticket punch which embodies 30 a preferred form of the invention is shown, it will be noted that the improved punch comprises levers or handles 15 and 16 pivoted to each other by a pin 17.

The handles 15 and 16 are provided with jaws 35 20 and 21, respectively. The jaw 21 is provided with ticket-receiving slots 22 and 23. The free end of the jaw 20 is provided with a punch pin 24 which may be projected through apertures 25 and 26 provided in the jaw 21 on either side of 40 the slot 23. The purpose of this construction will presently appear.

A compression spring 28 disposed between the handles 15 and 16 yieldingly holds them in the positions wherein they are shown in Fig. 1.

A punch member 30 is movably mounted on a plunger 30a which is pivoted loosely to the jaw 29 by a pin 31 which passes through a slot 32 provided in the plunger 30a (Figs. 2, 5 and 8).

The punch member 30 is provided preferably 50 with a substantially flat top surface 33, the edges of which co-operate with the bottom edges of a slot 34 formed in the jaw 21.

The punch member 30 is notched as at 38, the notch being formed with vertically disposed sur-

5

55

faces 39 and 40 and with a surface 41 disposed at a slight angle to the horizontal. Cutting edges 42 and 43 are formed where the surfaces 39 and 40 meet the surface 33.

5 Referring to Fig. 8, it will be noted that the top surface 33 of the punch member 30 normally lies flush with the bottom surface of the slot 22. It is readily understood that if the handles 15 and 16 are displaced toward each other against the 10 action of the spring 28, the punch member 30 will move upwards in the slot 34 and that certain edges of the top surface 33 will co-operate with the lower edges of the slot 34 to sever a unit or a "ride" from a ticket 10 which is shown in 15 Fig. 10. The edges of the punch member 30 which perform this cutting operation are identified by the reference characters 45 and 46 in Fig. 9. After one of the units 11 has been severed from 20 the ticket 10, the operator, if he is manipulating the punch properly, should continue to displace the handles 15 and 16 toward each other so that the severed unit 11 will be driven up into the slot 34.

The second punch member or die 48 projects 25 into the slot 34 and into the path of the severed section 11 which is pushed upwards through the slot 34. The die 48 engages a small square 11a of the severed section 11. A tension spring 49 has one end secured to the die 48 and has its 30 other end secured to a pin 50 which projects from the jaw 21. The spring 49 yieldingly holds the die 48 in the position wherein it is shown in Fig. 8, but when the severed section 11 is pushed upwards through the slot 34, the die 48 moves upward with the severed section 11 against the action of the spring 49 until it strikes a shoulder 52 provided in the jaw 21 (Fig. 8). Continued displacement of the punch member 30 towards the top of the slot 34 will cause the die 48 to co-operate 35 with the cutting edges 42 and 43 to sever the small square 11a from the severed section 11 so that the spring 49 may retract the die 48 and drive the severed square 11a down into the notch 38. The square 11a thus severed from the section 11 will 40 be ejected from the punch through a slot 55 provided in the jaw 21.

It will be noted that the punch member 30 is provided with a downwardly extending stem 30b slidably journaled in a bore 30c formed in the 50 upper end of the plunger 30a. Interposed between the punch member 30 and the bottom surface of the bore 30c is a compression spring 30e which yieldingly urges the punch member 30 upwardly.

Obviously, if no ticket 10 has been inserted in 55 the slot 22, the handles 15 and 16 may be displaced toward each other and the punch 30 and the plunger 30a will move upwardly without any appreciable compression of the spring 30e. If a ticket is inserted in the slot 22, the spring 30e will 60 be compressed before the punch member 30 severs a section 11 from the ticket.

As best shown in Figs. 5, 6, 7 and 9, a dog 70 has its lower end pivotally mounted in a notch 71 provided in the plunger 30a. The upper end of the dog 70 is beveled as at 72 and engages a cam surface 73 formed in a notch 74, the notch 74 being cut into the lower end of the punch member 30. The dog 70 is provided with an outwardly projecting finger or lug 75. A leaf spring 76 fixed 70 to the plunger 30a tends to hold the dog 70 in the position wherein it is shown in Figs. 6 and 9. However, if there is any displacement between the punch member 30 and the plunger 30a, sufficient to compress the spring 30e as illustrated in Fig. 7, the cam surface 73 will co-operate with the

beveled surface 72 to displace the dog 70 from the position wherein it is shown in Fig. 6 to the position wherein it is shown in Fig. 7. If, when the dog 70 is in the position in which it is illustrated in Fig. 6, the plunger 30a and the punch member 30 are driven upwardly, the finger or lug 75 will not engage a lever 78 pivoted to the jaw 21 by a pin 79. But, if the dog 70 has been displaced into the position wherein it is shown in Fig. 7, it will strike and displace the lever 78 when the plunger 30a and the punch member 30 are driven upwardly in the jaw 21.

Mounted on the jaw 21 are counters 80 and 81 of well known construction, the counters 80 and 81 being provided with actuating levers 82 and 83, 15 respectively, which will actuate the counters when they are displaced angularly.

One end of the lever 78 is engageable with the lever 83 and the lever 82 is engageable by a finger 85 pivoted by a pin 86 to the die 48 (Figs. 2 and 20 8). The finger 85 is held normally by a leaf spring 88 in the position wherein it is shown in Fig. 2, the leaf spring 88 being secured to the die 48. Formed integral with the lever 78 is a finger 90 which will engage and displace the finger 85 25 angularly against the action of the spring 88 when the lever 78 is displaced from the position wherein it is shown in Fig. 2 to the position wherein it is shown in Fig. 4. The lever 78 is adapted to be displaced in this direction by the 30 finger or lug 75 in the manner described above when a ticket occupies the slot 22 so that the spring 30e is compressed during the ticket punching operation. When the finger 85 is displaced by the finger 90 to the position wherein it is shown in Fig. 4, it displaces the lever 82 angularly during the upward movement of the die 48 and actuates the counter 80. In the event no ticket occupies the slot 22 when the handles 15 and 16 are 35 displaced toward each other, the finger or lug 15 does not displace the lever 78 angularly during the upward movement of the punch member 30 and the plunger 30a. This prevents the finger 90 from angularly displacing the finger 85 and the finger 85 does not actuate the counter 80. 40 It is also obvious that if no ticket occupies the slot 22 during upward movement of the punch member 30, the lever 78 will not be displaced angularly to actuate the counter 81. However, if a ticket occupies the slot 22 and the punch 45 member 30 is manipulated in such manner that a section 11 is severed from the ticket 10 but is not driven upwards in the slot 34 to sever the square 11a from the severed section 11, the finger or lug 75 will be displaced into the position wherein it is 50 shown in Fig. 4 so that it will cause the lever 78 to actuate the counter 81, but as the plunger 30a is not given a full stroke, the upper end of the pin 85 will not engage the lever 82 to actuate the counter 80. Therefore, it will be readily understood that if a ticket 10 occupies the slot 22, the counter 81 will register each time a section 11 or a part thereof is severed from the ticket even though the square 11a is not severed from the section. The counter 80 will register only when 55 substantially the full section 11 is first severed from the ticket and the square 11a is subsequently severed from the section. The difference between the totals on the two counters will indicate the number of times the punch was operated 60 improperly while a ticket 10, or the equivalent, occupied the slot 22 in the manner illustrated in Fig. 8 and in addition, this difference will indicate the number of times the punch was operated 65 improperly by inserting the ticket 10 into the slot 70 75.

22 such a short distance that the die 48 was not displaced upwardly even though the punch member 30 was displaced through a full stroke. Thus, if a conductor inserts the ticket 10 into the slot 22 a short distance so that the punch member 30 severs a small portion of the ticket during its upward stroke and this portion does not project beneath the die 48, the upward movement of the punch member 30 will not result in like movement of the die 48 and the die 48, in turn, will not displace the finger 85 upwardly to actuate the counter 80. Therefore, if a conductor, through inadvertence or in an attempt to avoid the severing of a full section 11 from the ticket 10 simply inserts the ticket a short distance into the slot 22, the counter 81 will register, but the counter 80 will not register. Therefore, unless the conductor places the ticket correctly in the slot 22 and actuates the punch member 30 through its full stroke, the counter 80 will not register and the difference between the total on this counter and the total on the counter 81 will indicate the total number of times the conductor fails to manipulate the punch properly when he is punching tickets. As set forth above, if no ticket is placed within the slot 22, the punch may be manipulated without actuating either of the counters 80 and 81.

Mounted on the jaw 21 is a bell 61. The clapper 60 fixed to the die 48 is adapted to strike the bell 61 so that an audible signal will be given when the die 48 is retracted by the spring 49 after a square 11a has been severed from a section or "ride" 11. This audible signal indicates that a ticket has been punched correctly. If the punch is operated to punch a ticket and the audible signal is not heard, it is an indication that the punch was actuated improperly.

The counters 80 and 81, the lever 78 and the fingers 75, 85 and 90 are preferably enclosed by a housing 95 which is detachably secured to the jaw 21 by screws 96. An eye 97 projecting from the jaw 21 and through a flange of the housing 95 is adapted to receive a sealing device 98 which must be left intact by the conductor when the punch is returned to the railroad company to be audited. Of course, the seal 98 will be replaced by a new seal after the auditing operation.

The ticket 10 is of usual construction and has the sections 11 indicated thereon by suitable markings. Fig. 11 illustrates the manner in which the square 11a is severed from a section 11.

The improved punch may also be employed in connection with tickets which are good for only one ride. If such a ticket is inserted in the slot 23 and the handles 15 and 16 are displaced toward each other, the punch pin 24 will cut a small disc from the ticket indicating that it has been cancelled.

Referring now to Figs. 12 to 14, inclusive, wherein a punch embodying another form of the invention is shown, the reference characters 115 and 116 designate the handles of the punch which comprises jaws 120 and 121, respectively. The handles 115 and 116 and the jaws 120 and 121 are identical in construction with the handles 15 and 16 and the jaws 20 and 21 described above, the jaw 121 being provided with ticket receiving slots 122 and 123 which correspond to the ticket receiving slots 22 and 23, respectively. The jaw 121 is provided with ticket punch apparatus which is identical in construction with the ticket punch apparatus mounted in the jaw 21, described above, and it functions in the same manner. Projecting from the ticket punch ap-

paratus of the jaw 121 is a finger 175 which corresponds to the finger 75 of the punch shown in Figs. 1 to 9, inclusive. The finger 175 is carried by a dog 170 which is identical in construction with the dog 70 described above, and is displaced in the same manner when the punch is operated to sever a section 11 from a ticket 10.

If no ticket is placed in the slot 122 when the handles 115 and 116 are displaced toward each other, the finger 175 is not displaced outwardly into the path of a lever 178 which is pivoted by a pin 179 to the jaw 121. However, when a ticket is placed in the slot 122 and the punch is operated, the parts of the punch which correspond to the punch member 30 and the plunger 30a, described above, displace the finger 175 into the path of the lever 178 and it and the finger, displaces the lever 178 from the position wherein it is shown in Fig. 12 to the position wherein it is shown in Fig. 13.

A pin 200 projects from a die member 148 which corresponds to the die 48, described above. The pin 200 is reciprocated with the die 148 each time a small square 11a is severed from a section or unit 11. The free end of a lever 202 lies in the path of the pin 200 and is pivoted by a pin 203 to a reciprocating member 204. The member 204 forms part of a counter 205 which is actuated each time the member 204 is reciprocated through the proper distance. The lever 202 is provided with a notch 206 engageable by a finger 207 formed on the lever 178. The lever 202 is yieldingly urged against the pin 200 by a leaf spring 210.

If it is assumed that a ticket 10 is placed in the slot 122 in the proper manner and that the punch is operated properly to first sever a section or unit 11 from the ticket and then sever a square 11a from the severed section 11, it will be readily understood that the pin 200 will displace the lever 202 in a counter-clockwise direction (Figs. 12 and 13) against the action of the spring 210 and withdraw the notch 206 from engagement with the finger 207 so that when the finger 175 displaces the finger 207 from the position wherein it is shown in Fig. 12 to the position wherein it is shown in Fig. 13, the finger 207 will not actuate the member 204 and the counter 205 will not register. However, if the ticket is not inserted in the slot 122 sufficiently far to cause the die 148 to be lifted during the ticket punching operation, the lever 202 will not be swung up out of the path of the finger 207 and the finger 207 will engage the notch 206 to reciprocate the lever 202 and the member 204. Such displacement of the member 204 causes the counter 205 to register. Therefore, the counter 205 will register each time the punch is operated improperly and it will indicate the total number of times the punch has been operated improperly over any given period of time.

The counter 205 and the actuating mechanism therefore are preferably enclosed within a housing 195 which corresponds to the housing 95, described above, and is secured to the corresponding jaw in the same manner and by similar means.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to

claim all novelty inherent in my invention as broadly as possible, in view of the prior art.

I claim:

1. A ticket punch comprising means for severing a section from a ticket, a counter for recording each time a section is severed from a ticket, means for severing a portion of said section from it, and a second counter for recording each time a portion of a section is severed from it. 5
10. 2. A ticket punch comprising means for severing a section from a ticket, a counter for recording each time a section is severed from a ticket, means for severing a portion of said section from it, a second counter for recording each time a portion of a section is severed from it, and means for giving an audible signal to indicate that said portion has been severed from said section. 10
15. 3. A ticket punch comprising means for severing a section from a ticket, means for severing a portion of said section from it, and means for recording each time a section is severed from a ticket without subsequently severing a portion of said section from it. 15
20. 4. A ticket punch comprising a punch member having means for severing a section from a ticket and means for severing a portion of said section from it, and a counter for recording each incomplete stroke of said punch member when a section is severed from a ticket. 20
25. 5. A ticket punch comprising a punch member for severing a section from a ticket and for severing a portion of said section from it, a counter for recording each incomplete stroke of said punch member when a section is severed from a ticket, and audible means for indicating each time a portion is severed from a section. 25
30. 6. A ticket punch comprising a punch member for severing a section from a ticket, a counter for recording each time a section is severed from a ticket, means for severing a portion of said section from it, and a second counter actuated by said punch member for recording each time a portion of a section is severed from it. 30
35. 7. A ticket punch comprising a pair of handles pivoted to each other, jaws carried by said handles, one of said jaws being provided with an aperture, a punch member slidably mounted in the last mentioned jaw and co-operating with said aperture to sever sections from tickets, a plunger slidably mounted in the last mentioned jaw, re- 35
40. silent means between said punch member and said plunger, means operatively connecting said plunger to the other jaw, a counter, and means responsive to displacement of said punch member relative to said plunger for actuating said counter. 40
45. 8. A ticket punch comprising means for severing a section from a ticket, means for severing a portion of said section from it, and a counter movable means actuated by said punch for recording on said counter the number of portions severed from sections independently of the number of sections severed from tickets. 45
50. 9. A ticket punch comprising a punch member for severing a section from a ticket and for severing a portion of said section from it, and a counter for recording each time said punch member is actuated to sever said section from a ticket but in such manner that said portion is not severed from said section. 50
55. 10. A ticket punch comprising a punch member for severing a section from a ticket and for severing a portion of said section from it, a counter for recording each time said punch member is actuated to sever said section from a ticket but in such manner that said portion is not severed from said section, and audible means for indicating each time a portion is severed from a section. 55
60. 11. A ticket punch comprising means for severing a section from a ticket, means for severing a portion of said section from it, counting mechanism, and movable means engageable by said section for actuating said counting mechanism to record each time a section is severed from a ticket without subsequently severing a portion of said section from it. 60
65. 12. A ticket punch comprising means for severing a section from a ticket, means for severing a portion of the section, and recording mechanism controlled by both the aforesaid means indicating the successful operation of the first named means and the failure of the second named means. 65
70. 13. A ticket punch comprising means for severing a section from a ticket, means for severing a portion of the section, and means for recording each operation of the punch in which one severing operation is completed and the other is not. 70

ALFRED R. JORGENSEN.

50
